United States Patent Office

Des. 190,572
Patented June 13, 1961

190,572

MODEL AIRPLANE

Bobby Lamar McDaniel, Columbus, Ga., assignor to Charlton H. Williams, Opelika, Ala.

Filed Aug. 15, 1960, Ser. No. 61,752

Term of patent 7 years

(CL. D34—15)

FIG. 1 is a top plan view showing my design of a model airplane.

FIG. 2 is a left side elevation of the model airplane shown in FIG. 1.

FIG. 3 is a bottom view of the model airplane shown in FIG. 1.

FIG. 4 is a view from tail end of the model airplane shown in FIG. 1.

The dominant features of my design reside in the portions shown in full lines.

I claim:

The ornamental design for a model airplane as shown and described.
